UNITED STATES PATENT OFFICE.

JACOB P. TIRRELL, OF CHELSEA, ASSIGNOR TO AMOS B. TAYLOR AND
GEORGE F. PINKHAM, OF WOLLASTON, MASSACHUSETTS.

LOOM-SHUTTLE.

SPECIFICATION forming part of Letters Patent No. 351,225, dated October 19, 1886.

Application filed February 10, 1886. Serial No. 191,513. (No model.)

To all whom it may concern:

Be it known that I, JACOB P. TIRRELL, a citizen of the United States, residing at Chelsea, in the county of Suffolk and State of Massachusetts, have invented certain Improvements in Loom-Shuttles, of which the following is a full, clear, and exact description, reference being had to the accompanying drawings, making part of this specification, in which—

10 Figure 1 is a central vertical section through a portion of a shuttle constructed in accordance with my invention. Fig. 2 is a horizontal section through the same, on the line $x\ x$ of Fig. 1, with the cop in place upon the expanded spindle. Fig. 3 is a central vertical section of the shuttle with the spindle raised. Fig. 4 is a transverse vertical section on the line $y\ y$ of Fig. 1. Fig. 5 is a section on the line $z\ z$ of Fig. 3, showing the cop in place upon 20 the spindle before the latter has been expanded.

My invention relates to that class of loom-shuttles which are provided with split spindles adapted to be expanded when closed down 25 into the shuttle to hold the cop firmly in place; and my invention consists in the combination, with the shuttle-body and a split spindle pivoted therein, of a rocking pivoted wedge extending around, beneath, and in front of the heel of the same and vertically upward through 30 the split of the said spindle, above which it is preferably provided with a lip or projection, which prevents the wedge from dropping down out of the split as the spindle is raised 35 on its pivot out of the shuttle, the relative positions of the pivots of the spindle and wedge being such that as the spindle is raised that portion of the wedge within the split will be drawn back toward the heel of the spindle 40 into an enlarged or recessed portion of the split, thus allowing the two portions of the spindle to close together to permit the cop to be easily slipped thereon, while when the spindle is closed down into the shuttle the 45 wedge will be forced forward in the direction of the length of the spindle into the narrow portion of the split, and thus caused to expand the spindle to hold the cop firmly in place, as hereinafter more particularly set forth.

In the said drawings, A represents the shut-

tle-body, of the usual form, within a cavity or recess, a , at one end of which is pivoted, at b , the spindle B, upon the top of the heel or base c of which bears the ordinary flat spring, d . 55 The spindle B is split lengthwise from near the point entirely through the heel, and when raised out of the cop-chamber e of the shuttle its two parts, $f\ g$, are intended to lie nearly in contact with each other, as seen in Fig. 5, to 60 allow of the cop G being easily slipped thereon or the cop-tube to be removed therefrom.

Within a central slit in the under side of the shuttle-body A, beneath and in the rear of the pivot b of the spindle B, is pivoted, at i , in line 65 with the axis of the spindle, a wedge-plate, D, of the form seen in Figs. 1 and 3, which fits within the central split of the heel of the spindle and extends around in front of the said heel and upward through the split k , between the 70 two portions $f\ g$, above which it is provided with a turned-over lip or other suitable projection or enlargement, m , as seen in Fig. 4, the purpose of which is to prevent the wedge 75 from dropping or working down out of the split k as the spindle is raised on its pivot out of the shuttle. That portion, n , of the split k immediately in front of the heel c is slightly enlarged or recessed out, as seen in Figs. 2 and 5, its front end being preferably inclined on each 80 side at 10 toward the narrower portion of the split, and the pivots $b\ i$ of the spindle and wedge are so placed with respect to each other that the said spindle and wedge will rock in arcs of circles eccentric to each other, and thus 85 when the spindle is raised that portion of the wedge D which lies within the split will be drawn backward toward the heel c into the enlarged or recessed portion n , which thus allows the two portions $f\ g$ of the spindle to come 90 close together, as seen in Fig. 5, to permit the cop G to be easily placed thereover.

When the spindle is closed down into the shuttle, the wedge D is rocked downwardly on its pivot i by the friction of the two portions 95 $f\ g$, which pinch it tightly between them, and as it descends in the arc of a circle eccentric to that in which the spindle moves, it is forced forward toward the point of the spindle, against the inclines 10, and into the narrower portion 100 of the split k in front of the same, as seen in Fig. 2, thus separating the two parts $f\ g$ and

expanding the spindle against the hollow interior of the cop G, which is thereby held securely in place, as desired.

By thus employing a pivoted rocking wedge which extends up from beneath through the split of the spindle and remains permanently therein, and is adapted to be moved backward and forward in the direction of the length of the spindle as it is rocked on its pivot, instead 5 of a stationary wedge adapted to enter the split only when the spindle is closed down into the shuttle, and be withdrawn entirely from the said split when the spindle is raised, the operation of expanding the spindle is facilitated 10 and accomplished with less power on account of the increased leverage produced by pivoting the wedge in the manner described, which insures the spindle being carried by the action 15 of its spring *d* fully down to its horizontal position in the cop-chamber *e*, as required.

I claim—

1. The combination, with a shuttle-body and a split spindle pivoted therein, of a wedge, *D*, pivoted on a stationary pin, *i*, and rocking in 25 an arc of a circle eccentric to that in which the spindle moves, and extending around in front of the heel of the spindle, and having a vertical portion extending up through the split of the spindle in a direction at right angles to its 30 length, and adapted to remain permanently within said split and be moved backward and forward therein in the direction of the length of the spindle as it is rocked on its pivot-pin *i*, whereby the spindle is expanded as it is 35 closed down into the shuttle and contracted as it is raised out of the same, substantially as set forth.

2. The combination, with the shuttle-body *A* and its pivoted split spindle *B*, of the rocking pivoted wedge *D*, extending around in front 40 of the heel of the spindle and upward through the split *k*, and adapted to remain permanently within said split and be moved backward and forward therein in the direction of the length of the spindle as it is rocked on its pivot, and 45 having a lip or projection, *m*, on that portion which extends above the spindle, whereby the wedge is prevented from dropping or working down out of the split as the spindle is raised on its pivot out of the shuttle, substantially 50 as described.

3. The combination, with the shuttle-body *A*, of the pivoted spindle *B*, having a split, *k*, provided with an enlarged or recessed portion, *n*, and the wedge *D*, pivoted on a stationary 55 pin, *i*, and rocking in the arc of a circle eccentric to that in which the spindle moves, and extending around in front of the heel of the spindle, and having a vertical portion extending up through the split of the spindle in a direction at right angles to its 60 length, and adapted to remain permanently within said split and be moved backward into the said enlarged or recessed portion *n* of the same as the spindle is raised out of the shuttle, substantially as 65 and for the purpose set forth.

Witness my hand this 30th day of January, A. D. 1886.

JACOB P. TIRRELL.

In presence of—

P. E. TESCHEMACHER,
W. J. CAMBRIDGE.
